UNITED STATES PATENT OFFICE.

HAROLD ROWNTREE, OF CHICAGO, ILLINOIS, ASSIGNOR TO THE BURDETT-
ROWNTREE MANUFACTURING COMPANY, OF CHICAGO, ILLINOIS, A COR-
PORATION OF ILLINOIS.

ELEVATOR-DOOR-OPERATING MECHANISM.

SPECIFICATION forming part of Letters Patent No. 700,375, dated May 20, 1902.

Application filed November 29, 1901. Serial No. 83,965. (No model.)

To all whom it may concern:

Be it known that I, HAROLD ROWNTREE, a citizen of the United States, residing at Chicago, in the county of Cook and State of Illinois, have invented a new and useful Improvement in Elevator-Door-Operating Mechanism, of which the following is a specification.

This invention relates to elevator-door-operating mechanism.

10 The object of the invention is to provide an elevator-door-operating mechanism wherein the doors are positively and quickly operated or shifted by power mechanism into open or closed position.

15 A further object of the invention is to provide means for automatically controlling the opening and closing movements of the door, so that the door-operating mechanism may be put in operation for each door as the car 20 reaches a particular landing at which it is to stop.

25 A further object of the invention is to provide a door-operating mechanism for elevator wells or shafts wherein the speed of travel of the door in moving from its open to its closed position or from its closed to its opened position is variable and wherein the speed of travel of the door is reduced as it approaches its extreme closed or opened position.

30 Other objects of the invention will appear more fully hereinafter.

The invention consists, substantially, in the construction, combination, location, and arrangement of parts, all as will be more fully 35 hereinafter set forth, as shown in the accompanying drawings, and finally pointed out in the appended claims.

Referring to the accompanying drawings and to the various views and reference-signs 40 appearing thereon, Figure 1 is a view in front elevation of an elevator well or shaft door, showing the application thereto of a construction embodying the principles of my invention. Fig. 2 is a view in side elevation, parts 45 in vertical section. Fig. 3 is an enlarged broken detail view, in side elevation, of a form of door-operating mechanism embodying the principles of my invention. Fig. 4 is a similar view, in front elevation, of the construc-

tion shown in Fig. 3. Fig. 5 is a detail view 50 in section on the line 5 5 of Fig. 3 looking in the direction of the arrows. Fig. 6 is a broken detail view, in front elevation, showing the door-operating gear forming part of the form of construction shown in Figs. 3 and 4, the 55 driving-pinions being omitted. Fig. 7 is a broken detail view in section, showing the centering-stop arrangement of the construction shown in Figs. 3 and 4. Fig. 8 is a broken detail view in section, showing the manner of 60 connecting the door-operating lever or arm to the door. Fig. 9 is a view similar to Fig. 4, showing a modified form of construction embraced within the spirit and scope of my 65 invention.

The same part is designated by the same reference-sign wherever it occurs throughout the several views.

In carrying out my invention in the form of constructions shown in Figs. 1 to 9, inclusive, I employ a shaft A, arranged to extend throughout the height or length of the elevator shaft or well. This shaft may be continuously rotated or driven from any suitable source of power and from which the door-operating mechanism is driven. Arranged adjacent to each elevator shaft or well door and in convenient position with reference thereto on any fixed part of the framework of the enclosure is a bracket B, upon which is pivotally mounted one end of an arm or lever C, the other end of said arm or lever being slidably connected, as at D, in any suitable or convenient manner to the elevator shaft or well door E. Also suitably journaled upon 80 the bracket or framing B is an operating bevel-gear or other suitable driving part F. Suitably mounted upon to rotate with shaft A, but capable of movement longitudinally with respect to said shaft, is a sleeve G, carrying oppositely-presented pinions H H'. A shifting lever J is pivotally mounted upon the bracket or casting or other convenient part of the framework in position for one arm thereof to engage a collar K on sleeve G and with the other end or arm thereof arranged in suitable or convenient position to be engaged by a shiftable shoe or other suitable 90 95

means carried by the car and indicated at L in Fig. 1. A spring or other retractile M may be connected to lever J to normally hold said lever in position to maintain the sleeve G in one of its limits of movement and also in position for said lever J to be engaged by a shoe or other suitable part upon the car and which may be shifted in a well-understood manner by the car-conductor whenever it is desired 5 to open any particular door. Suitably pivoted at one end eccentrically upon bevel-wheel F is a link N, the point of pivotal connection of said link being indicated at O. The other end of said link is pivotally connected, 10 as at Q, to the arm or lever C. A number of the gear-teeth of bevel-gear F are omitted, as at P, the purpose of which will presently be explained more fully.

The operation of the apparatus so far described is as follows: When a car approaches 15 or reaches any particular landing at which it is desired to stop or at which it is desired to open the elevator shaft or well door, the car-conductor effects an actuation of the shoe L or other device to project the same into engaging relation with respect to lever J, thereby 20 rocking said lever against the action of its retractile M, and hence causing a displacement of sleeve G along shaft A and in a direction to enable pinion H' to be brought into meshing relation with respect to gear F and the same movement carrying pinion H out of 25 position to mesh with said gear F, and inasmuch as continuous rotation is imparted to shaft A, and hence also to sleeve G and pinions H H', the intermeshing of pinion H' when thus shifted with gear F will effect a rotation 30 of said gear—for instance, from the position of the parts shown in Figs. 1 and 4. Rotation thus imparted to gear F effects a swinging of arm C, as indicated in dotted lines in 35 Fig. 4, through the connection of link N, respectively, with said gear and arm, thereby effecting a movement or shifting of the door 40 into open position. By reason of the path described by the crank or eccentric connection O of link N to gear F it will be observed that the opening movement of the door begins slowly, and such speed gradually 45 increases until the crank or eccentric connection O traverses the first half of its complete travel—that is, one-quarter of a complete revolution of wheel F. From this point inward to the end of the travel of eccentric or crank connection O it will be seen that the speed thereof gradually decreases, thereby imparting a decreasing speed of travel to the door toward its completely-opened position, the speed of travel of the door being gradually 50 reduced as it approaches its complete opened position, finally coming to rest when the crank or eccentric O has traveled through an arc of one hundred and eighty degrees. The position of the parts at this position—that is, with 55 the door in completely-opened position—is indicated in dotted lines in Fig. 4, and it will be observed that the points Q and O are sub-

stantially in line with the axis of rotation of gear F—that is, the link N occupies a position of a dead-center with reference to its points of connection to gear F and arm C. Consequently the door will be held locked in its open position. When this point is reached, the rotation of gear F is arrested by reason of the space P, where the omitted teeth of gear 75 F occurs, being brought into position opposite pinion H'. The parts remain in this position until it is desired to close the door. The operator on the car thereupon releases the shoe L or other similar device, thereby permitting 80 lever J to return to its normal position, and hence shifting sleeve G into the position thereof as disclosed in Figs. 3 and 4, with pinion H' out of meshing or engaging relation with respect to gear F and with pinion H brought 85 into engaging relation with respect to said gear. Thereupon rotation is imparted to gear F in the opposite direction to that above described until the portion P of the gear-surface thereof arrives opposite pinion H, when the 90 rotation of gear F will be arrested. During this return rotary movement of gear F it will be seen that the arm C is returned to its initial position and the door shifted or moved into closed position. It will also be seen that 95 in closing the door will start from rest at a gradually-increasing speed until gear F makes one-half of its return movement—that is, one-quarter of a complete revolution thereof—and from that point on to its initial position, as 100 shown in Fig. 4, the movement of the door is of decreasing speed until the door is finally brought to rest in its closed position. It will also be seen that when the door reaches its closed position the points O and Q of pivotal 105 connection of link N to gear F or arm C, respectively, are again brought into substantial line with the axis of rotation of gear F, and hence in the position of a dead-center, thereby locking the door in its closed position. Thus 110 it will be seen that I provide an exceedingly simple and inexpensive mechanism for positively operating elevator shaft or well doors to open and closed positions, wherein the shifting movements of the door are effected by 115 power mechanism which is under the control of the car-conductor and which is put in operation or in operative connection with the door only when desired. It will also be seen 120 that the mechanism provides in itself for varying the speed of travel of the door in opening or closing, so that the door will be brought to its positions of rest in completely open or closed positions at a decreasing speed of movement, thereby being relieved of shock or jar, 125 and that the door is locked in such positions.

If desired and in order to prevent gear F, through momentum or otherwise, from being carried beyond the point where the space P in the gear-surface thereof is brought opposite the pinions H H', as the case may be, I may provide suitable stops R in convenient position upon the gear F to coöperate with a stop-pin S or other suitable device to posi-

tively arrest gear F and prevent the same from being carried beyond its proper stopping-point.

It may sometimes be desirable to insure complete disengagement of the teeth of pinions H H' from the teeth of gear F when the point P in said gear is brought opposite said pinions and to prevent possibility of the teeth of pinions touching the adjacent or bounding teeth of space P of gear F during the continuous rotation of said pinions. This result may be accomplished in many different ways. I have shown a simple and convenient manner of accomplishing this object by arranging stop-pin S to be acted upon by a spring A', normally operating to press said pin into contacting relation with the periphery of gear F, and in the periphery of said gear at points adjacent to the stops R, formed thereon, I provide V-shaped grooves B', adapted to receive the pointed end of pin S. From this construction and arrangement it will be seen that when gear F reaches its position of rest—that is, such position as will bring the space P opposite the pinion H or H' which is in meshing relation with respect to the teeth of said gear F—the end of pin S will enter the seat formed by the recesses B', thereby efficiently holding the gear F in position for the teeth thereof to be out of mesh with the pinion H or H', as the case may be, the inclined walls of said seats in coöperation with the pointed end of pin S permitting gear F to take up rotation in the opposite direction whenever the other pinion H or H' is shifted into engaging relation with respect to said gear.

It may sometimes be desirable to provide for the proper actuation of the driving element of the door-operating mechanism without bodily disengaging the driving-pinions, still retaining the feature of a continuously-revolving shaft. I have shown such a construction in Fig. 9, wherein instead of shifting the pinions H² H³ into and out of meshing relation with respect to drive-gear F' said pinions are mounted to revolve freely upon shaft A and in constant mesh with the teeth of gear F', and each pinion H² H³ is provided with a clutch, with which coöperates a clutch-sleeve G', adapted to be mounted upon shaft A to rotate therewith, but capable of movement longitudinally thereof, the shifting of said sleeve G' being effected by a lever J' in the same manner as that above described with reference to lever J. Thus when it is desired to open the door the sleeve G' is shifted from the car in the manner above described to lock one or the other of the pinions H² H³, as the case may be, to rotate with shaft A, the other of said pinions running free upon said shaft, and, similarly, the shifting of sleeve G' in the opposite direction will connect the other of said pinions to rotate with shaft A, thereby actuating gear F' in the opposite direction from that above mentioned and correspondingly shifting the door. The gear F'

is provided with a vacant space similar to the space P, as above described and for a similar purpose, and the link connection from gear F' to the door-operating lever remains the same and the operation being the same. The advantage of the construction shown in Fig. 9 is that the pinions H² H³ are not required to be shifted into or out of meshing relation with respect to the teeth of gear F'. 75

It is obvious that many other specifically different forms of construction would occur to persons skilled in the art, whereby the results had in view are accomplished. I do not desire, therefore, to be limited or restricted to the exact constructions shown and described; but,

Having now set forth the object and nature of my invention and a construction embodying the principles thereof, what I claim as new 85 and useful and of my own invention, and desire to secure by Letters Patent, is—

1. In an elevator-door-operating mechanism, the combination with a door, power mechanism for operating the same including a rotatable shaft, a rotating part driven therefrom, and eccentric connections between said rotating part and door, whereby the door when operated is moved at constantly-varying speed, as and for the purpose set forth. 90

2. The combination with a door, of operating mechanism therefor including a rotatable shaft, a rotating part driven therefrom, eccentric connections between said door and rotating part, and means for controlling the operation of said rotating part, as and for the purpose set forth. 100

3. The combination with a door, of an operating mechanism therefor including a rotatable shaft, a rotating part driven therefrom, 105 an arm or lever connected to the door, and a link eccentrically connected to said rotating part and having connection with said arm or lever, as and for the purpose set forth.

4. The combination with a door, of an arm or lever connected thereto, a rotatable shaft, a rotating part adapted to be driven therefrom, a link connected to said arm or lever and eccentrically connected to said rotating part, and means controllable from the car for 110 operating said rotating part, as and for the purpose set forth. 115

5. The combination with a door, a gear, a rotatable shaft, driving connections intermediate said shaft and gear for imparting rotative movement to said gear, a link pivotally connected eccentrically to said gear, and connections between said link and door, as and for the purpose set forth. 120

6. The combination with a door and a rotatable shaft, of a rotatable gear adapted to be driven from said shaft, a link pivotally connected eccentrically to said gear, an arm connected to the door and to which said link is also connected, the point of connection of said link to said gear and arm being in substantial alinement with each other and with

the axis of rotation of said gear when the door is in closed or opened position whereby the door is locked, as and for the purpose set forth.

7. The combination with a door, power mechanism for operating the same and including a rotatable shaft, a rotating part driven therefrom, connections between said rotating part and door for moving the same into closed or opened position, said connections operating in starting the door from a position of rest to move the door with a steadily-increasing speed, and at a steadily-decreasing speed as the car approaches its limit of movement, and means for controlling the operation of said power mechanism, as and for the purpose set forth.

8. The combination with a door, power mechanism for operating the same including a driving-shaft, pinions mounted on said shaft, a gear coöperating with said pinions, a link pivotally connected eccentrically to said gear, and connections between said link and door, as and for the purpose set forth.

9. The combination with a door, power mechanism for operating said door, including a gear, driving-pinions for said gear, connections between said gear and door, said gear provided with a blank space in the gear-face thereof, whereby it is brought to rest, as and for the purpose set forth.

10. The combination with a door, of a continuously-revolving shaft, pinions mounted upon said shaft, a gear, means for operatively connecting said gear and shaft through said pinions, a portion of the teeth of said gear being omitted, and connections between said gear and door, as and for the purpose set forth.

11. The combination with a door, of an operating mechanism therefor, including a gear having a portion of the teeth omitted therefrom, a continuously-revolving shaft, pinions mounted thereon, means whereby said pinions complete operative connection between said gear and shaft, a link pivotally connected to said gear, and connections between said link and door, as and for the purpose set forth.

12. The combination with a door, of operating mechanism therefor, including a rotatable gear, a rotating shaft, pinions actuated thereby and forming operative connections between said shaft and gear, means for governing the operative connections between said pinions and gear, whereby either one or the other of said pinions are made operative with respect to said gear, and stops for arresting the movement of said gear, as and for the purpose set forth.

13. The combination with a door, of an op-

erating-gear therefor, said gear provided with lugs, pinions for actuating said gear, and means arranged to be engaged by said lugs for arresting said gear at proper positions with reference to said pinions, as and for the purpose set forth.

14. The combination with a door, an operating-gear therefor having a portion of the teeth thereof omitted, pinions for actuating said gear, whereby said gear is arrested when the blank portion thereof arrives opposite an actuating-pinion, and means for maintaining said gear in position to hold said blank portion out of engagement with the operating-pinion, as and for the purpose set forth.

15. In an apparatus of the class described, the combination with a door-operating mechanism therefor, including a rotatable gear having a portion of the gear-teeth thereof omitted to form a blank space, driving-pinions for said gear, said gear provided with notches or seats in the periphery thereof, and means arranged to enter said notch or seat to maintain said gear in position to hold said pinions out of engaging relation with respect to said gear, as and for the purpose set forth.

16. The combination with a door, of operating mechanism therefor, including a shaft, a sleeve mounted upon said shaft for rotation therewith, but capable of movement lengthwise thereof, means controllable from the car for shifting said sleeve upon said shaft, a gear, pinions, the shifting of said sleeve effecting the operative connection of one or the other of said pinions with said gear, a link pivotally connected eccentrically to said gear, and connections between said link and door, as and for the purpose set forth.

17. The combination with a door, of mechanism for operating the same, including a gear, a rotatable shaft, a sleeve mounted upon said shaft for rotation therewith, but capable of longitudinal movement thereon and carrying pinions arranged when said sleeve is shifted to be brought respectively into engaging relation with respect to said gear, means for controlling the shifting movements of said sleeve from the car, a link pivotally connected at one end eccentrically to said gear, and means connected to the other end for operating the door, as and for the purpose set forth.

In witness whereof I have hereunto set my hand, this 26th day of November, 1901, in the presence of the subscribing witnesses.

HAROLD ROWNTREE.
